COMPUTING INSTRUMENT FOR MAKING
ELBOWS

Vernon W. Dalzell, Alliance, Ohio

Application May 26, 1952, Serial No. 289,966

4 Claims. (Cl. 235—61)

1

The invention relates to a protractor particularly adapted for use in the making of elbows for determining the height of rise of the miter line.

An object of the invention is to provide a calculator by means of which elbows of two or more pieces or sections, for connecting two runs of pipe at any desired angle, may be easily and quickly made.

Another object is to provide such a device by means of which an elbow of any desired construction, for use upon pipe of any known diameter, may be quickly and easily constructed.

A further object is to provide such a device comprising two members pivotally connected together, the lower member having a straight upper edge and having spiral curved lines scribed thereon, the upper member having its upper edge graduated in inches or other units of measurement and having a perpendicular edge adjacent to the pivot point and located at 90° to said graduated edge.

A still further object is to provide such a calculator in which the several spiral curves upon the lower member indicate the number of pieces or sections of which the elbow is to be made.

The above objects together with others which will be apparent from the drawing and following description, or which may be later referred to, may be attained by constructing the improved calculator in the manner hereinafter described in detail and illustrated in the accompanying drawing, in which:

Fig. 1 is a top view of a calculator embodying the invention, showing the parts adjusted for the making of an elbow for connecting two runs of pipe located at a predetermined angle to each other;

Fig. 2 a diagrammatic view showing the manner in which the angle of offset of the two runs of pipe to each other is determined;

Fig. 3 a developed view of one section of an elbow showing the manner in which the pattern for the section is obtained from calculations made upon the calculator;

Fig. 4 a side elevation of an elbow which may be constructed by use of the calculator; and,

Fig. 5 a diagram showing the manner in which the spiral curve may be plotted by the coordinate system.

Referring first to the calculator illustrated in Fig. 1, the device may be formed of two members comprising the lower plate, indicated generally at 10, and the upper plate, indicated at 11, both of which may be formed of any suitable material, preferably a transparent plastic material, such as

2

is ordinarily used for the making of draftsmen's triangles and the like.

The lower member 10 has the straight upper edge 12 and one perpendicular edge 13 at right angles to the straight edge 12. The upper member 11 has the graduated top edge 14, which may be graduated in inches as shown, or may have metric system graduations thereon, if desired.

This upper member has the perpendicular edge 15 located at 90° to the graduated edge 14, and is pivotally connected to the lower member 10 at the upper left hand corner thereof, as by the pivot screw 16 upon which is located a nut 17 for locking the two members in any desired adjusted position.

The lower member 10 has a calculator formed thereon comprising a plurality of equally spaced radial lines, radiating from the pivot point 16 and extending from the vertical line indicated at 0° to the horizontal line indicated at 90°, or even greater angles.

The particular embodiment of the calculator illustrated is a 10 inch size, being especially adapted for use in obtaining the measurements for sections of an elbow for use with a 10 inch diameter pipe.

It should be understood that the calculator may be made in various sizes, for various other diameters of pipe, although, as will be later described in detail, the measurements for elbows to fit other diameters of pipe may be quickly and easily computed from this 10 inch size calculator.

A spiral, curved line 18 is scribed upon the top surface of the lower member 10, extending from the pivot point 16 to the point where it intersects the horizontal 90° radial line 19 at a point exactly 10 inches from the pivot point.

In Fig. 5 is shown a diagram indicating the manner in which this spiral curved line 18 may be determined by the coordinate system. It should be understood that this diagram is shown on a much smaller scale than the calculator in Fig. 1, being one-fourth the size thereof.

In plotting this curve by the coordinate system 45 the initial line 20 is drawn of a length exactly twice the diameter of the pipe for which the calculator is designed, in the present case the line 20 being 20 inches long.

At the exact center of the line 20 the origin or pole 21 is located and with this center the semi-circular arc 22 is drawn connecting at opposite ends with the ends of the initial line 20.

A plurality of radius vectors, as indicated at 23, are drawn from the pole 21 to the arc 22, being preferably located at angles of 5° to each other

3

throughout the entire arc. Starting with the vertical radius vector **23a**, indicated at 0° , the radius vectors to the left thereof are indicated at 5° to 90° , and starting at the right of the radius vector **23a** they are indicated reversely from 85° to 0° .

At the point of intersection of the initial line **20** with the left side of the arc **22** is formed a secondary pole **24**, from which secondary vectors, as indicated at **25**, radiate and intersect the arc **22** at the points of intersection therewith of the radius vectors **23** indicated at 85° to 0° on the right side of the arc.

The points **26**, at which the secondary vectors **25** intersect the radius vectors **23** of like number, determine the spiral curve **18** which is then drawn through the points **26**. This spiral curved line **18** upon the calculator, as shown in Fig. 1, is used in conjunction with the graduated edge **14** of the top member **11** to determine the height of rise of the miter line where a two-piece or two-section, elbow is to be made.

Similar spiral curved lines indicated at **27**, **28**, **29**, **30**, **31**, **32** and **33** are scribed upon the top surface of the lower member **10** for use in determining the rise of the miter line where 3, 4, 5, 6, 7, 8 or 9 sections respectively are to be produced for making the elbow.

In using the improved calculator for making an elbow, it is first necessary to determine the angle of offset between the two runs of pipe to be connected. This may be done as indicated in the diagram of Fig. 2 in which the lines **33'** and **34** indicate the two runs of pipe to be connected.

The straight edge **12** of the lower member **10** of the calculator may be placed against the line **34** and the upper member **11** of the protractor swung upon the pivot point **16** until the perpendicular edge **15** of said upper member is lined up with the line **33'**. This locates the graduated edge **14** of the upper member **11** at a 60° angle as indicated on the calculator shown in Fig. 1.

Another way to determine this setting of the calculator is to extend the line **33'** above the line **34** as indicated in dotted lines at **33a** in Fig. 2, and then measure the angle between the line **34** and the extension **33a** which is shown to be 60° . The upper member **11** of the calculator is then moved to the 60° position as shown in Fig. 1.

The workman then decides whether to make the elbow in two or more sections. If he is to make the elbow of two sections he then takes the reading upon the graduated edge **14** where the same intersects the spiral curved line **18**, which as shown on Fig. 1, is $5\frac{3}{4}$ inches. This is the height of rise of the miter line for a two-piece elbow.

Assuming that the workman decides to make the elbow of three sections, he takes a reading upon the graduated edge **14** of the upper member at the point where it intersects the spiral curved line **27** which, as shown on Fig. 1, is about $2\frac{1}{4}$ inches. This is the height of rise of the miter line for the first section of the three-piece elbow.

To lay out this section of the elbow the workman then draws a circle as indicated at **35** in Fig. 3, the diameter of which is $2\frac{1}{16}$ inches. He then draws a horizontal line, as indicated at **36** in Fig. 3, at any distance below the circle **35** which may be desired for additional length in the section for telescoping with the adjacent end of one run of the pipe.

A vertical line **37** is drawn through the center of the circle **35**, perpendicular with the hori-

4

zontal line **36**. This vertical line forms the center of the pattern for this section of the elbow. The horizontal line **36** is extended an equal distance to each side of this center, the length of the horizontal line from the points **38** to **39** being equal to the circumference of the section of the elbow.

The circle is then divided into 12 equal parts as indicated by the radial lines **40**, and the horizontal line **36** is divided into 12 equal parts, as indicated by the vertical lines **41**. Horizontal lines **42** are then drawn through the radial division **40** of the circle and intersect the vertical lines **41**.

15 A curved line **44** is then drawn through the points of intersection **43** of the vertical and horizontal lines **41** and **42** respectively, and this curve will be the upper edge of this section of the elbow.

As shown in Fig. 4 this section of the elbow is 20 shown in side elevation at **45**. The maximum height **46** of the middle section **47** of this elbow will be twice the maximum height **43** of the section **45**, or twice the height of rise of the miter line plus any additional length desired to give the 25 proper center line radius. The third section **49** of the elbow will be the same as the section **45**, plus any additional length which may be desired for telescoping with the pipe.

It will thus be seen that with this improved 30 angle protractor an elbow of any desired number of sections for connecting together two runs of pipe located at any angle to each other may be quickly and easily plotted.

The above description has reference to the 35 making of an elbow for a pipe of 10 inches in diameter. If elbows are to be made for pipes of smaller or larger diameter the calculator may be made in such smaller or larger sizes as may be required.

40 However, by using the 10 inch calculator as illustrated, measurements may be quickly computed for the making of elbows of larger or smaller diameter. For instance, in the event that an elbow is to be made for a 5 inch pipe, the reading upon the graduated edge **14** of the upper member of the calculator, where the same intersects any one of the curved lines **18** or **27** to **33**, may be divided by 2.

45 For instance, if a three-section 60° elbow is to be made for a 5 inch diameter pipe, the reading of $2\frac{1}{16}$ inches will be divided by 2, the height of rise of the miter line being $1\frac{1}{32}$ inches.

If an 8 inch diameter elbow is to be made, four-fifths or .8 of the reading upon the graduated edge **14** will be taken as the height of rise of the miter line, etc.

50 If, on the other hand, a larger diameter pipe is used, the reading upon the graduated edge of the upper member of the calculator may be added to. For instance, assuming that an elbow is to be made for a 12 inch diameter pipe the height of rise of the miter line will be $1\frac{1}{5}$ or 1.2 times the reading upon the graduated edge **14**, etc.

55 Although the protractor is shown as designed 60 for making an elbow for connecting two runs of pipe located at an obtuse angle to each other, it will be possible with the same type of calculator to design an elbow for connecting two runs of pipe at an acute angle to each other. This may be accomplished by increasing the height of the lower member **10** of the protractor so as to project the curved lines **18** and **27** to **33** beyond 90° to a maximum of approximately 135° .

70 In the foregoing description, certain terms 75 have been used for brevity, clearness and under-

standing, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

I claim:

1. A device for determining the height of rise of the miter line for making elbows, said device comprising a lower member, an upper member having a straight edge graduated with a scale of linear measurements thereon, means pivoting the end of the upper member to one end of the lower member, there being a spiral curved line on the lower member extending from the pivot point toward the other end thereof and indicating an elbow having a definite number of sections, whereby in a predetermined relative position of the upper member upon the lower member the point of intersection of the graduated edge of the upper member with the spiral curved line on the lower member indicates the height of rise of the miter line for a particular elbow formed of a predetermined number of sections.

2. A device for determining the height of rise of the miter line for making elbows, said device comprising a lower member, an upper member having a straight edge graduated with a scale of linear measurements thereon, means pivoting the end of the upper member to one end of the lower member, there being a spiral curved line on the lower member extending from the pivot point toward the other end thereof, said spiral curved line being plotted by the coordinate system and indicating an elbow having a definite number of sections, whereby in a predetermined relative position of the upper member upon the lower member the point of intersection of the graduated edge of the upper member with the spiral curved line on the lower member indicates

the height of rise of the miter line for a particular elbow formed of a predetermined number of sections.

3. A device for determining the height of rise of the miter line for making elbows, said device comprising a lower member, an upper member having a straight edge graduated with a scale of linear measurements thereon, means pivoting the end of the upper member to one end of the lower member, there being a plurality of spiral curved lines on the lower member extending from the pivot point toward the other end thereof and indicating a plurality of elbows each having a definite number of sections, whereby in a predetermined relative position of the upper member upon the lower member the point of intersection of the graduated edge of the upper member with any spiral curved line on the lower member indicates the height of rise of the miter line for a particular elbow formed of a predetermined number of sections.

4. A device for determining the height of rise of the miter line for making elbows, said device comprising a lower member, an upper member having a straight edge graduated with a scale of linear measurements thereon, means pivoting the end of the upper member to one end of the lower member, there being a plurality of spiral curved lines on the lower member extending from the pivot point toward the other end thereof, said spiral curved lines being plotted by the coordinate system and indicating a plurality of elbows each having a definite number of sections, whereby in a predetermined relative position of the upper member upon the lower member the point of intersection of the graduated edge of the upper member with any spiral curved line on the lower member indicates the height of rise of the miter line for a particular elbow formed of a predetermined number of sections.
